VARIABLE RESISTANCE AUXILIARY ELECTRICAL RECEPTACLE FOR ELECTRICAL LIGHTING APPLIANCES

Roger A. McArron, Somerset, Ohio

Application July 17, 1951, Serial No. 237,234

3 Claims. (Cl. 201—63)

1

The present invention relates to auxiliary electrical receptacles, and has particular reference to an improved electrical receptacle for electric lighting appliances which incorporates an electrical resistance element for automatically controlling the voltage supplied from a source of current to an electrical lighting appliance or fixture in a manner governing the illumination of the lighting appliance or fixture.

The primary object of the present invention is to provide an auxiliary electrical receptacle with which an electrical lighting appliance or fixture may be connected, and which functions, upon energization of an operating circuit for the lighting fixture or appliance, to initially reduce the voltage supplied to an incandescent lamp carried in the appliance and to progressively increase such voltage in a manner whereby the electric lighting instrumentality will be first caused to glow, and thereafter increase in illuminating intensity to substantially its maximum illuminating capacity, to thereby eliminate a sudden and intense illumination of the lighting instrumentality upon closure of its operating circuit, and at the same time to reduce the detrimental effects to the filament of the lamp occasioned by a sudden surge of current upon closure of the operating circuit for the lighting instrumentality.

It is another object of the invention to provide an auxiliary electrical receptacle which incorporates a resistance element having a negative temperature-resistance coefficient which is connected in series with the operating terminals of the receptacle in a manner by which an electric lamp or other lighting fixture electrically connected with the terminals of the receptacle may, upon energization of its operating circuit, be supplied with a relatively low voltage immediately following energization of the operating circuit, and which thereafter functions to progressively increase the amount of voltage passing to the lighting fixture in a manner to cause the filament thereof to initially glow in a subdued light and progressively increase in intensity to substantially its maximum candle power output.

Electrical receptacles formed in accordance with the present invention find particular value when used in connection with a lighting appliance to produce a bedroom or bathroom night light, whereby, upon closure of the operating circuit for the lighting fixture, the lamp bulb will be caused to initially transmit light rays of relatively low intensity and thereafter increase in illumination to prevent harmful and painful

2

shock to the optical nerves of a person occupying a previously darkened room, or a person having just awakened from sleep.

For a further and more detailed understanding of the present invention, and the various additional objects and advantages realized therefrom, reference is to be had to the following description and the accompanying drawing, wherein:

10 Fig. 1 is a perspective view of an auxiliary electrical receptacle formed in accordance with the present invention;

Fig. 2 is a medial longitudinal vertical sectional view taken through the receptacle;

15 Fig. 3 is a detailed horizontal sectional view taken along the line 3—3 of Fig. 2; and

Fig. 4 is a circuit diagram of an electrical lighting circuit incorporating the present auxiliary receptacle.

20 Referring now to the drawing, the numeral 5 designates generally the present auxiliary resistance-containing electrical receptacle which comprises an outer tubular cylindrical casing 6, the walls of which are perforated substantially throughout its entire area, and which is preferably formed from a high heat conductivity metal, such as copper. Each end of the perforate casing 6 is formed to provide an annular radially and inwardly projecting rib 7, and the end portions of the casing 6 are split longitudinally, as at 8, a distance inwardly from the ends thereof to provide resiliently expandable clamping portions.

25 Carried in the upper end portion, as viewed in Fig. 2, is a cylindrical end member 9 which is formed from any suitable dielectric material, such as porcelain, or one of the dielectric resins of the phenol formaldehyde type. The upper end member 9 is formed to provide a pair of internal sockets 10 which open outwardly of the member 9 by way of a pair of terminal-receiving slots 11 through which the male terminal prongs of an electric lighting appliance, not shown, may be inserted. Extending within the sockets 10, and

40 rigidly carried by the dielectric end member 9, are a pair of spring-type electrical contacts 12 whose separate leg portions define slots in registration with the openings 11 of the end member 9. The bifurcated contacts 12 are arranged so as to be resiliently expanded upon insertion therein of the usual male terminal extensions associated with lighting fixtures.

45 A similar dielectric end member 13 is carried within the opposite or lower end of the casing 6, and has embedded therein a pair of male ter-

minal prongs 24 which extend outwardly from the lower end of the member 13 in relatively spaced non-shorting relation and for insertion within the separate female sockets of the usual wall-mounted electrical receptacle, not shown. The male terminals 14 extend completely through the dielectric end member 13 and terminate at their inner ends in angularly related webs 15.

Electrically connecting the right-hand contact 12 with the right-hand male terminal prong 14, as viewed in Fig. 2, is an electrical conductor 16 having one end suitably connected with the inner end of the contact 12 and its opposite end connected with the web 15 of the right-hand terminal 14, such as by soldering. The intermediate portion of the conductor 16 is insulated from electrical contact with the outer casing 6 by means of an outer covering 17 of dielectric material.

Connected between the opposite or left-hand contact 12 and the male terminal prong 14 is a bank composed of a plurality of cylindrical resistance elements 18 having separate end leads 19 extending through suitably spaced openings formed in a pair of circular spacer disks 20 disposed at either end of the resistance elements 18. The end leads 19 have their outer end extremities wound together into a single manifold conductor 21 which is soldered to the inner end portions of the left-hand contact 12 and terminal prong 14. In this manner, the separate resistance elements 18 are electrically connected in parallel, while the entire bank of resistance elements forms a series connection between the left-hand terminal prong 14 and the contact 12. It will be understood, that the spacer disks 20 may be formed from any suitable dielectric material, such as mica, fiber board, or a suitable dielectric resin, and function to maintain the individual resistance elements 18 in relatively spaced relationship and in spaced relation to the inner wall surface of the outer casing 6.

For purposes of assembly, I have found it advantageous to initially assemble the bank of separate resistance elements 18 together with the spacer disks 20 and the wound manifold end extensions 21 to provide a unit, and in assembling the separate elements of the receptacle, the lower manifold 21 of the resistance elements is initially soldered to the web 15 of the left-hand male terminal 14 of the lower end member 13. Similarly, the conductor 16 is soldered to the web 15 of the right-hand terminal 14, and thereafter, the lower end of the casing 6 is resiliently snapped over the inner end of the member 13 and forced downwardly upon the member 13 until the inwardly directed flange engages a peripherally disposed groove 22 formed in the member 13. The upper manifold 21 and the upper end of the conductor 16 are then drawn outwardly through the upper end of the casing 6, and soldered to the respective terminals 12 of the upper end member 9, it being understood that the conductor 16 and the end extensions 19 of the resistance elements 18 are of a sufficient length to permit the same to be drawn outwardly of the opposite ends of the casing 6. After soldering of the conductor 16 and manifold 21 to the contacts 12, the upper end member 9 is forced into the upper end of the casing 6 until the inwardly projecting annular rib 7 of the casing lodges within the cooperative groove 22 of the upper member 9. In this manner, the respective end members 9 and 13 are securely locked within the outer casing 6 to pro-

vide a rigid unitary structure containing the resistance elements 18 in spaced non-shorting relationship to the conductor 16.

As previously stated, the resistance elements 18 are of a type having a negative temperature-resistance coefficient, whereby the resistance of each element decreases in direct proportion to the heat of the element. In this connection, each of the resistance elements 18 may comprise a resinous or ceramic material having a metallic oxide incorporated therein which, at ordinary temperatures, has a high resistance, but which decreases in resistance in direct proportion to the heat established within the resistance element through energization of an operating circuit associated therewith.

Fig. 4 of the drawing discloses a circuit diagram embodying the present resistor-type receptacle. In Fig. 4, the reference characters L1 and L2 designate the power lines for the ordinary household alternating current circuit which, in the usual manner, is provided with outlet receptacles, not shown, throughout a house or building, into which the terminals 14 may be inserted. By connecting the terminals 14 within the female sockets of the ordinary wall-mounted receptacle, the usual male terminal prongs of an electric light fixture or appliance may thereafter be inserted within the sockets 10 of the end member 9 for electrical engagement with the contacts 12. Upon closure of a switch 23 which is normally associated with the electrical lighting appliance, which carries an incandescent lamp bulb 24, current is caused to flow through the resistance elements 18 to initially decrease the voltage passing to the filament of the lamp 24, whereupon the filament will glow with a subdued light and thereafter progressively increase in intensity with an increase in temperature of the resistance elements 18. By properly proportioning the resistance of the elements 18 in association with the wattage of the incandescent lamp 24, the time required for an increase in illuminating power of the lamp 24 from a relatively light glow to substantially its full intensity may be varied in accordance with the desires of the user. In this connection, I have found it advantageous to employ a total resistance which will enable the incandescent lamp 24 to attain approximately 85 per cent efficiency in approximately one and one-half minutes after closure of the control switch 23 and initial energization of the operating circuit for the lamp. In this manner, a room to be illuminated by the lamp 24 is not thrown into sudden brilliant illumination upon closure of the switch 23, but is lighted gradually with an increase in intensity by nature of the varying resistance of the elements 18.

Also, due to the initial decrease in voltage passing to the filament of the lamp 24, the same is protected against shock due to an otherwise sudden surge of operating current to the filament of the lamp upon closure of the switch 23. In this manner, the life of the lamp 24 is materially increased over similar lamps which are subject to immediate current flow upon energization of its operating circuit.

The outer casing 6, which is preferably formed from a high heat conductivity metal, such as copper, which enables heat emanating from the resistance elements 18 to be quickly and rapidly dissipated from the receptacle, and due to its perforate nature, free circulation of air may be had through the receptacle to further reduce the temperature thereof.

In view of the foregoing, it will be seen that the present invention provides a unique and useful auxiliary electrical receptacle for use in connection with electrical lighting appliances to initially reduce the degree of illumination of an associated incandescent lamp bulb upon energization of the operating circuit therefor, but which, following initial energization, permits the bulb to attain substantially maximum illuminating power. Thus, use of the present receptacle in connection with an electric lamp results in an efficient and safe night lamp for use in bedrooms or bathrooms of a home to prevent the damaging effect of immediate illumination of a darkened room to a person awakening from sleep.

While a preferred embodiment of the invention has been disclosed in detail, it will be understood that various modifications as to constructional details is comprehended without departing from the spirit of the invention or the scope of the following claims.

I claim:

1. An auxiliary receptacle for electrical lighting appliances comprising a receptacle frame provided at one end with a dielectric member defining socket means for the reception of the male terminals of an electrical lighting appliance; a pair of electrical contacts positioned in said socket means for circuit-making engagement with the male terminals of an electrical appliance received in said socket means; a pair of male terminals carried by and projecting outwardly from the opposite end of said frame for insertion within a female current-supplying receptacle; an electrical conductor connecting one of said electrical contacts with one of said male terminals; and an electrical resistance element having a negative temperature - resistance coefficient electrically connected between the other of said pair of electrical contacts and the other of said pair of male terminals, said resistance element serving to initially decrease the voltage passing through said receptacle to a lighting appliance connected therewith and thereafter to progressively increase said voltage to cause the lighting appliance to progressively increase in illumination following energization thereof.

2. In an auxiliary electrical receptacle for electrical lighting appliances; a receptacle body provided at opposite ends with dielectric members,

one of said members defining socket means for the reception of the male terminals of an electrical lighting appliance; a pair of electrical contacts positioned in said socket means in relatively spaced non-shorting relation and arranged to engage the respective male terminals of an electrical lighting appliance inserted in said socket means; a pair of male terminals carried by and projecting outwardly from the other of said dielectric members and disposed in relatively spaced non-shorting relation; conductor means electrically connecting one of said contacts with one of said male terminals; and an electrical resistance element having a negative coefficient of resistance connected between the other of said contacts and the other of said male terminals for initially decreasing the voltage passing through said receptacle to a lighting appliance connected therewith and thereafter to progressively increase said voltage to cause the lighting appliance to progressively increase in illumination following energization thereof.

3. An electrical receptacle for electrical lighting appliances comprising a receptacle body provided at one end with socket means for the reception of the male terminals of an electrical lighting appliance and at its opposite end with a pair of male terminals for electrical connection with a source of electrical energy; conductor means electrically connected between said socket means and said terminals; and electrical resistance means electrically connected with said conductor means and contained in said receptacle body and having a negative temperature-resistant coefficient, said receptacle being adapted to be connected between a lighting appliance and a source of electrical energy, and said resistance means serving, upon energization of the lighting appliance, to initially reduce the voltage for the appliance and thereafter to progressively increase the voltage to substantially the maximum voltage of said source.
